UNITED STATES PATENT OFFICE.

BORIS GORKIN, OF PLAINFIELD, NEW JERSEY.

WINDOW STRUCTURE.

Application filed July 1, 1925. Serial No. 40,844.

The present invention relates to improvements in window structures and particularly to show windows such as are used in front of stores and the like.

5 An important object of the invention is to provide an improved sill cover and ventilated sash for such windows.

Another important object of the invention is to provide a combination structure of this 10 nature which is exceedingly simple in its construction, leak-proof, strong, durable, efficient, reliable, and otherwise well adapted to the purpose for which it is designed.

With the above and numerous other objects in view as will appear as the description proceeds, the invention resides in certain novel features of construction, and in the combination and arrangement of parts 15 as will be hereinafter described and claimed more fully.

In the drawing—

Figure 1 is a sectional perspective view showing my improved combined sill cover and ventilated sash,

25 Fig. 2 is a sectional view through a corner bar,

Fig. 3 is a detail view of a bolt used with a connecting bar in a window structure, and

30 Fig. 4 is a sectional view taken on the line 4—4 of Fig. 3.

Referring to the drawing in detail, it will be seen that 1 designates a sill having the usual riser 2 thereon a distance from the front edge thereof. A sill cover 3 is disposed over the front edge of the sill 1 in the usual manner and as a hook flange in its upper edge. A ventilating sash A is disposed on the sill and includes the rear portion formed from an intermediate plate 5, an upper plate 6, and lower plate 7, all of 35 an integral formation. A depending flange 8 is provided on the end of the upper plate 6 and a hook flange 9 is formed on the edge or end of the bottom plate 7 and interfits 40 with the hook flange 4 so as to provide a leak-proof joint.

The front plate 10 of the ventilating sash has at its upper end a depending flange 11 and at its lower end an inwardly extending flange 12 which abuts the inter-fitting joint 45 formed by the hook flanges 4 and 9. The window pane 13 is received between the flanges 8 and 11. The front plate 10 is held clamped against the pane and in engagement

with the leak-proof joint 4, 9, by means of 55 screws 14. The front plate 14, of course, is provided with suitable ventilating openings 16.

Bars are usually placed at the corners of the window structure so as to hold the glass 60 together and also where the two panes meet in the same plane. An improved structure of these bars is shown in Figs. 2 to 4 inclusive. The bar consists of two plates 17 having adjacent oppositely disposed hook 65 flanges 18 at their abutting edges which are held together by a plate or strip 20 having curved over flanges 19 engaging the flanges 8 thereby forming a hinge which is easily 70 adjusted to different angles. Retaining bolts 75 are associated with the bars for holding them in place and consist of heads 21 corrugated as is shown at Fig. 4. These heads may be changed as is shown in Figs. 2 and 3 to conform to the plates 17 depending 75 whether they are disposed on the corner or where two panes meet in the same place. Shanks 22 extend from the central portions of the heads 21.

It is thought that the construction, utility, 80 and advantages of my invention will now be clearly understood without a more detailed description thereof. It is desired, however, to point out that numerous changes in the details of construction, in the materials, in 85 the combination and arrangement of parts, may be resorted to without departing from the spirit or scope of the invention as hereinafter claimed or sacrificing any of its advantages.

Having thus described my invention, what 90 I claim as new is:—

A bar for window construction, including a pair of plates disposed alongside of each other and having their adjacent edges provided with hooked flanges extending in opposite directions, a strip having hooked edges for engagement with the hooked flanges for forming a hinge which holds the pair of plates together, and bolts having 95 corrugated elongated heads engageable with said plates and said strip to brace and hold the same assembled, said pair of plates having their other edges provided with hooked flanges for engaging over the ends of the 100 elongated heads of the bolts.

In testimony whereof I affix my signature.

BORIS GORKIN.
